(57) **CLAIM**

The ornamental design for a nozzle for electronic atomizing device, as shown and described.

DESCRIPTION

FIG. 1 is a perspective view of a nozzle for an electronic atomizing device showing an embodiment of our design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is an enlarged top plan view thereof; FIG. 8 is an enlarged bottom plan view thereof; FIG. 9 is a perspective view of a nozzle for an electronic atomizing device showing another embodiment of our design; FIG. 10 is another perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is an enlarged top plan view thereof; and, FIG. 16 is an enlarged bottom plan view thereof.

The broken lines in the drawings depict portions of the nozzle for electronic atomizing device that form no part of the claimed design.

The oblique shade lines in the drawings show transparency.
